UNITED STATES PATENT OFFICE.

CHARLES M. CARR, OF SAN DIEGO, CALIFORNIA.

BUTTONHOLE-MAKING MACHINE.

1,333,832.

Specification of Letters Patent. Patented Mar. 16, 1920.

Application filed January 18, 1918. Serial No. 212,407.

To all whom it may concern:

Be it known that I, CHARLES M. CARR, a citizen of the United States, residing at San Diego, in the county of San Diego and State 5 of California, have invented an Improvement in Buttonhole-Making Machines, of which the following description, in connection with the accompanying drawings, is a specification.

- 10 My invention relates to button-hole making machines, and particularly to that part of such machine which regulates the number of stitches to a given size of button-hole and indicates to the operator of the machine
- 15 on a graduated dial or scale in view of the operator the relative number of stitches that the machine will make in a given size button-hole. The number of stitches necessary to properly make a button-hole varies with
- 20 the size of the button-hole, and provision is made in all button-hole making machines for adjusting it to cause the proper number of stitches to be made in a given size of button-hole; but, so far as I am informed, no
- 25 device has been invented that indicates the position where the stitch regulator is to be placed so that the proper number of stitches will be used in the button-hole desired to be made. It is desirable that such an indicator be applicable to any button-hole making machine without materially changing the structure or organization of the parts of the machine, or of the cutting, stitching or sewing mechanisms of the device.
- 30 For the purpose of providing an indicator of the class mentioned that is capable of accomplishing the end desired, and also have the necessary characteristics of adaptability to various machines, I have produced my
- 35 invention, which consists of a means for showing on a graduated dial on the top of the base of the button-hole making machine in view of the operator, the point at which the stitch regulator must be set to furnish
- 40 the predetermined number of stitches for any size button-hole to be made.
- 45

In the drawings herewith I show my device as an attachment to a standard Singer Sewing Machine Company's standard button-hole making machine, as shown in United States Patents Nos. 743,212 and 743,213, November 3, 1903, E. B. Allen.

50 My device includes a means attached to the stitch regulator which enables the operator of the button-hole making machine to readily change the number of stitches by simply

turning a wrench member without first turning the button-hole making machine out of its ordinary working position, as is at present required on button-hole making machines. 60

The structure and operation of my device will be more fully described in the specifications which follow, and it is illustrated in the accompanying drawings which 65 form a part of my specification.

While I have shown my invention combined with a standard Singer Sewing Machine Company's type of button-hole making machine, as shown in United States Patents 70 Nos. 743,212 and 743,213, November 3, 1903, E. B. Allen, and have described this embodiment in these specifications, I do not wish to be limited by these specifications, as my device may be applied to any standard make 75 of button-hole making machine without materially changing its structure.

In the drawings like characters refer to like parts throughout.

Figure 1 is a plan view of my improved 80 indicating finger and dial; Fig. 2 is a front elevational view of my device complete; Fig. 3 is a side elevational view of same showing in section the dial; Fig. 4 is a detail plan view of the operating lever with 85 a portion broken away; Fig. 5 is a sectional, elevational view of a portion of a standard Singer button-hole making machine with a portion broken away and showing my device attached thereto; Fig. 6 is a bottom plan 90 view of the guide for my adjusting device; Fig. 7 is a bottom plan view of a part of a standard Singer button-hole making machine with my device attached thereto and Fig. 8 is an elevational view of my device 95 complete showing in section portions of the button-hole making machine.

Numeral 1, (Fig. 7) is the swinging arm of a button-hole making machine α , which is pivotally mounted at one end on the pivot 100 2 of said machine α , and is adapted to be swung on said pivot 2 for the purpose of imparting an intermittent rotary movement to the feed cam by an oscillating movement imparted to said arm 1 from the rock shaft 10 and a link 3. The link 3 is pivotally mounted at 4 on a pivot 5. The pivot 5 is provided with a tapering head portion 6 which is adapted to reciprocate in the channel 7 of the swinging arm 1. The link 3 is secured 110 on said pivot 5 by a nut 8. The link 3 is pivotally connected to the rock shaft 10 by the

ball pivot 11, so as not to interfere with the partial rotation of the rock shaft 10.

A shaft 12, provided on its lower end with a toothed wheel 13 and on its upper end with a reduced threaded portion 14, passes through a dial 18. On the reduced threaded portion 14 is mounted an indicating finger 15 which is securely attached thereto by means of a nut 9. This shaft 12 is revolubly mounted in a bearing 16 which is firmly attached at its upper portion to the portion 17 of the dial 18. The dial 18 is adapted to be fastened to the base-plate *m* of the button-hole making machine *a* by bolts or screws inserted in the holes 19 and screwed into said base-plate *m* so that the bearing 16 passes through a hole drilled for that purpose in said base-plate *m* at 20.

The dial 18 is provided with a graduated scale 21 showing in figures $\frac{1}{4}$, $\frac{1}{2}$, etc., thereon in fractional parts of an inch, the size of the button-hole to be stitched. The row *r* of figures indicates the position of the stitch regulator when heavy cotton thread is used, and the row *p* of figures indicates the position of the stitch regulator when silk thread is used. The size of the button-hole, rather than the number of stitches to a button-hole, is marked on the dial 18 as the size of a button-hole is more generally understood than the number of stitches required to make it.

A coil spring 22, which rests against the lower end of the bearing 16 and the toothed wheel 13, is mounted on the shaft 12 to hold said shaft 12 in such a position that the finger 15 will be kept close to the surface of the dial 18.

Mounted on the end of link 3 is an enlarged double yoke member 23, shown best in Figs. 3 and 4. This member 23 is securely mounted on the link 3 by means of bolts 24 which are adapted to hold the opposite ends 25 and 26 of the yoke member 23 so that the middle of said end portions 25 and 26 will rest firmly on the enlarged portions 27 of said link 3.

Rigidly mounted on the member 23 is a support member 28 in which is mounted, near each end thereof, the cylindrical members 29 and 30. Mounted reciprocally in the cylinder 29 is a reciprocating member 31 and in the cylinder 30 is mounted a similar reciprocating member 32. On the ends of the members 31 and 32 is firmly mounted a toothed segment 33, which is adapted to engage with the toothed wheel 13. Mounted on each of the members 31 and 32 is a coil spring 34. These coil springs 34 rest against the segment 33 and the support 28 and by their pressure keep the member 33 constantly in engagement with the toothed wheel 13.

On the lower part of the table *b* on which the button-hole making machine *a* is sup-

ported and attached thereto by screws *m* over an elongated opening 35, there is provided a support *c* which is provided with a slot 36. Mounted in this slot 36 is a wrench member 37 which is provided on its upper end with a recess, the walls of which securely fit the nut 8 which the wrench member 37 is adapted to tighten or loosen by turning the member 37 by means of a handle portion 38.

Mounted on the member 37 between an annular projection 39 and a plate 40 resting on the support *c* is a coil spring 41. This spring 41 is adapted to hold the member 37 in engagement with the nut 8.

The button-holes are cut in the fabric by the knife 42 in the manner now provided by the standard button-hole making machines and this knife 42 is changed to suit the size of the button-hole required. This change is made by loosening the screw 43 and inserting the size of knife required and then tightening the screw 43.

As stated before in these specifications, the arrangement of the knife, stitching and sewing mechanisms of the button-hole making machine with which my device is used, is not changed in any manner whatsoever.

In operation the nut 8 is loosened by turning the wrench 37 sufficiently to permit of the end of the link 3 to be shoved along the slot 7 in either direction required. When the link 3 swings on the pivot 11 the teeth of the segment 33 will engage with the toothed wheel 13, thereby causing the shaft 12 to revolve, carrying with it the indicating finger 15; and when the proper size button-hole is indicated by the finger 15 the nut 8 is tightened and the link 3 will hold the stitch regulator 7 in this position until the nut 8 has been released.

What I claim and desire to secure by Letters Patent, is:

1. The combination with the stitch regulator of a button-hole making machine, of a stitch indicator comprising a link provided with a toothed segment, a shaft member provided with a toothed wheel in operative connection with said toothed segment, an indicating finger mounted on said shaft and a graduated dial adapted to be mounted on said button-hole making machine.

2. In a button-hole making machine, the combination with the stitch regulator of said button-hole making machine, of a link provided with a toothed segment, a shaft member provided with a toothed wheel in operative connection with said toothed segment, an indicating finger mounted on said shaft, and a dial provided with a graduated scale of sizes adapted to be mounted on said button-hole making machine immediately below said indicating finger.

3. The combination in a button-hole making machine of a stitch regulator, a rock

shaft mounted on said button-hole making machine, a link adjustably mounted at one end in a channel in said stitch regulator, and pivotally mounted on said rock shaft, a yoke member mounted on the end of said link, a support member provided with cylindrical bearings on each end, mounted on said yoke member, a toothed segment provided with bearings adapted to reciprocate in said 10 cylindrical bearings, a shaft member provided with a toothed wheel adapted to be revolved by said toothed segment, an indicating finger mounted on said shaft and a graduated scale adapted to be mounted on 15 said button-hole making machine immediately below said indicating finger.

4. The combination with a stitch regulator of a button-hole making machine, of a rock shaft mounted on said button-hole making machine, a link provided with a 20 toothed segment and at one end pivotally mounted on said rock shaft, a shaft provided with a toothed wheel adapted to be revolved by the swinging of said link and said segment, a graduated dial adapted to be mounted on said button-hole making machine, an indicating finger mounted on said shaft, and adapted to indicate on said graduated dial the size of button-hole to be made. 25

In testimony whereof, I have hereunto 30
subscribed by name.

CHARLES M. CARR.
